UNITED STATES PATENT OFFICE.

WILLIAM WHARTON, JR., OF PHILADELPHIA, PENNSYLVANIA.

IMPROVEMENT IN DISPENSING WITH SWITCHES ON RAILROADS.

Specification forming part of Letters Patent No. 26,454, dated December 13, 1859.

To all whom it may concern:

Be it known that I, WILLIAM WHARTON, Jr., of the city and county of Philadelphia, and State of Pennsylvania, have made a new and useful Improvement in the Method of Dispensing with Railroad-Switches; and I do hereby declare the following to be a full, clear, and exact description of the same, reference being had to the annexed drawings, making a part of this specification, in which—

Figure 1, Plate 1, represents an end view of a wheel having a tread upon each side of the flange. Figs. 2, 3, and 4, same plate, show several positions of the wheels and track.

The nature of my invention consists in dispensing with any form of switch now in use and substituting in place thereof a wheel provided with two or more treads or their equivalents, in combination with an additional raised rail or rails, either curved or straight.

I will now proceed to describe one of the means by which two sets of cars may use the same rail in part and then separate and go in different directions. An ordinary rail, either straight or curved, as desired, is laid, upon which cars provided with wheels of the ordinary form (*i. e.*, with a single tread, the flange being on the inner side) will run. At the point where it is proposed to change the route for another line of cars short inner rails are laid, having a gradual rise, upon which inner rail the inside tread of the double-tread wheels (represented in Fig. 1, Plate 1) shall run. These inner rails have a gradual rise sufficiently great to raise the car provided with the double-tread wheels high enough to pass over the rails of the ordinary track clear.

The mode of operation of this inner rail is as follows: Whenever the car provided with the wheels having double treads reaches an inner raised rail, it runs upon it by means of the inner tread, and being thereby raised entirely clear of the ordinary rail passes over it and follows the direction of the inner raised rail, whether curved or straight. After the car has passed a sufficient distance the inner rail may be discontinued, and an outer or ordinary rail may be substituted, upon which the outer tread of the wheels will run. The inner rail is raised as compared with the outer one. In many cases it may be desirable to

depress the outer rail either the whole or a part of the required distance, leaving the inner rail at or near the ordinary height.

Instead of using wheels of the shapes above mentioned, any shape may be used which provides an additional tread or treads either upon the inner or outer side of the ordinary tread. The additional raised rails are always so placed that such of the extra treads as desired shall run upon them, and may therefore be laid either inside or outside of the ordinary track at the points where it is desired to change the route. Different wheels having treads of the ordinary form, but of different widths, will thus of course be made to go upon different routes. At a certain point all the cars provided with wheels of a certain shape will, by means of the combination with the raised rails, be made to go upon a certain route. Other cars provided with wheels which will not run upon the raised rails as placed at that particular point will go upon a different route, and so continue until at another certain point, by means of raised rails properly placed, they will be acted upon by means of the proper extra tread or treads, and continue either upon a curved or straight route, as desired. Thus a number of different lines of cars may run upon the same track, and each line of cars as it arrives at the point properly arranged for it and not for the other lines will deviate from the course and go upon its own particular route.

In running through express trains drawn by locomotives it may be very desirable to use this combination, since such trains may be furnished with wheels with extra treads, which, in combination with raised rails properly placed for that purpose, will entirely disregard all turn-outs or branch roads and continue directly through from station to station, while trains provided with wheels of the ordinary form may, if desired, be operated on by switches moved in the ordinary or any other manner without in any way interfering with the arrangement as placed for the express-train alone. The height of the raised rails of course need not be greater than to allow the wheels intended to run upon them to pass over the other track. Such rise may be made so gradual that there will be no per-

ceptible inclination at all. Any requisite guide-rails may be used if found necessary to keep the wheels in their proper position.

Having thus described my improvement, I would observe in conclusion that I do not claim and therefore do not confine or restrict myself to the construction or shape of wheels which I have had occasion to describe or refer to, as variations may be made therefrom without deviating from the principle of my said invention; but

What I claim as my invention, and desire to secure by Letters Patent, is—

The employment of a car-wheel provided with one or more treads in addition to the ordinary tread, (upon either the outer or inner side of said ordinary tread and of the

same or different diameter as said ordinary tread,) in combination with additional raised rail or rails with a gradual rise, either curved or straight, so placed that such of the said extra treads, as desired, shall be caused to run upon them, thereby raising the car entirely clear of the ordinary track and causing it to follow the direction of said raised rail or rails, whether curved or straight, for the purpose of avoiding the necessity for railroad-switches, arranged and operating substantially as hereinbefore set forth.
